UNITED STATES PATENT OFFICE.

CHARLES GREEN, OF NEW YORK, N. Y.

SAMPLE-CARD.

1,132,337.

Specification of Letters Patent. Patented May 18, 1915.

Application filed April 18, 1914. Serial No. 832,773.

To all whom it may concern:

Be it known that I, CHARLES GREEN, a citizen of the United States, and a resident of the city of New York, borough of Brooklyn, county of Kings, and State of New York, have invented a new and Improved Sample-Card, of which the following is a full, clear, and exact description.

This invention relates to improvements in sample display cards, and has for an object to provide an improved structure wherein the card is properly held in place and a display tag is provided with a number or other identifying designation arranged thereon.

Another object of the invention is to provide a sample card which will properly hold in place display slips, and at the same time indicate the number or other designation of the material on the display slip, the designation being arranged so as to be prominently displayed, and to clearly indicate the particular slip with which it is associated.

In the accompanying drawings—Figure 1 is a plan view of a sample card embodying the invention; Fig. 2 is a section through Fig. 1 approximately on line 2—2; Fig. 3 is a detailed fragmentary perspective view showing one end of the display slip and the particular construction of the retaining member and display tab; Fig. 4 is a detailed fragmentary view of a display card with a slightly modified form of display slip connected thereto; Fig. 5 is a perspective view of a series of display cards connected together and arranged so as to be folded together, the same being shown on a reduced scale; Fig. 6 is a detailed fragmentary view showing a slightly modified form of the invention; Fig. 7 is a section through Fig. 6 on line 7—7.

Referring to the accompanying drawings by numeral, 1 indicates a card of any desired material, as for instance cardboard or pasteboard. Card 1 is provided with a plurality of slits or apertures 2. Associated with card 1 and coacting with the slits 2 are display slips 3 carrying or having secured thereto the goods 4 which are being displayed. The slips 3 are provided with notches 5 at each end, whereby an extension 6 is formed at each end. The extensions 6 are designed to be tucked or passed through the slits 2 on opposite sides of the card as clearly shown in Figs. 1 and 2 so as to hold the body of the slips 3 in the position shown

in Fig. 1 for displaying the goods 4. One of the extensions 6 is provided with a pressed-out portion or tab 7 as shown, particularly in Fig. 3. This pressed-out portion may be provided with a number, a letter or other information, whereby the particular goods arranged on the display slip 3 may be identified. When applying the slips 3 to the card 1 the extensions 6 are inserted or passed through the slits 2 and the tab 7 is bent or scop'd or slid over the outer surface of the card, as shown in Figs. 1 and 2, and the tab 7 as well as the number that is printed or prominently displayed on the slip 3, is held in position and strengthened by the application of the slip 3 over the surface of the card 1. The tab 7 over the surface of the card 1 is not weakened, only strengthened. It is not provided, whereby a comparatively weak card 1 need only be used and yet be sufficiently strong for insuring the durability of the device.

In Fig. 4 will be seen a slightly modified form of the invention in which both of the extensions 6' are provided with pressed-out portions or tabs 7, whereby a number, a letter or other designation may be printed on the outer surface of the slip 3. The position of the number, designation of this kind does not in any way weaken the card 1 or affect the durability. Removal and application of slip 3 does not affect the space reserved for the number. When using either form of the invention the same may be arranged on single cards as shown in Fig. 1, or may be arranged to form present a folder structure 8, as shown in Fig. 5. In forming the card 1 the same may be made of a single sheet and the slits 2 or openings 2 may extend entirely therethrough, but preferably a back sheet 9, as provided (Fig. 2) which may be secured to the front sheet by any means, as for instance a suitable adhesive 10, whereby the card 1 is really a double card formed from card 1 and front 11, as clearly shown in Fig. 2.

In Figs. 6 and 7 another form of the invention is shown wherein a reinforcing strip of metal 12 is used, which reinforcing strip of metal is preferably fabric of some strong kind. The fabric 12 may be secured in place by any desired means, as for instance a good quality of adhesive. It is to be noted that the fabric 12 covers not only the part of the extensions 6 which goes beneath the card but also the tab 7. This positively prevents any tearing or breaking during the use of the device. The rein-

forcement may be used not only upon the form of the invention shown in Fig. 1 but also upon the form of the invention shown in Fig. 4.

5. What I claim is—

1. In a display card, a body, a foundation provided with a plurality of slits arranged in parallel rows, a display slip formed with extensions fitting into each pair of parallel slits, and a pressed-out tab formed from one of said extensions, said pressed-out tab being arranged on the exterior of said body when the extension associated therewith is positioned beneath said body.
2. In a display card of the character described, a body provided with a pair of slits, a display slip provided with a projection at each end co-acting with said slits and adapted to be inserted therethrough, one of said extensions being provided with a pressed-out portion presenting a tab for receiving a number, said tabs being adapted to be positioned on the outer face of said card when the extension associated therewith is extended from one of said apertures and positioned beneath said body.

3. In a display card of the character described, a card provided with a pair of slits, a display slip provided with extensions adapted to extend through said slits and occupy a position in back of the card, each of said extensions being provided with a pressed-out portion adapted to occupy a position in front of said card when the extensions are occupying a position in back of the card.

4. In a display card of the character described, a plurality of display slips, each of said display slips being provided with a body for receiving matter to be displayed, an extension projecting from each end of said body, said extensions being smaller than the body, whereby shoulders are provided, and a number receiving tab pressed out of one of said extensions.

In testimony whereof I have signed my name to this specification in the presence of two subscribing witnesses.

CHARLES GREEN.
